MEANS FOR CASING CUTTING

Austin N. Stanton, Garland, Tex., assignor of fifty
per cent to John J. Fleet, San Antonio, Tex.

Application July 30, 1945, Serial No. 607,716

9 Claims. (Cl. 166—1)

1

This invention relates to apparatus for cutting, perforating and windowing well casing and it has particular reference to such apparatus for performing the functions set forth while the casing is suspended in a well.

A mixture of equal molecular parts of iron oxide and aluminum reacts exothermically to produce aluminum oxide and pure iron, producing a great deal of heat in the process. This is a well-known process and the mixture is marketed under the trade-name of "Thermit." It has a great many uses, chiefly in welding. Other similar mixtures which produce large amounts of heat at high temperatures and which contain within themselves all the elements necessary to complete the chemical reaction come within the meaning of this invention.

The present invention seeks, among its objects, to adapt this material, or similar materials, to the cutting, perforating or windowing of oil well casing or drill stems while the latter are suspended in the well. Present methods of cutting casing involve the lowering of a mill machine into the hole on the end of the drill stem, engaging the cutters with the casing and rotating the mill until the casing is cut off. Not only is considerable labor and time involved in lowering the mill but occasional mechanical difficulties are encountered, such as a broken drill stem, leaving junk in the hole, often with complete loss of the hole. Perforating is commonly done by means of guns which necessarily produce small and easily clogged holes in the casing and surrounding formations. While the gun may be lowered on a cable, it is of hard steel and if lost in the hole, may result in complete loss of the latter. Windowing is ordinarily done by knives lowered on drill stem and is subject to the same difficulties as the mill mentioned above.

It is therefore the prime object of the invention to provide an apparatus capable of performing any and all of the functions described and the device of the invention may, in any case, be attached to the end of a wire line for lowering the device into a well casing, thereby saving considerable time and labor.

Another object of the invention is to provide an apparatus of the character set forth capable of producing a number of cuts; a number of circular annular perforations or even several windows in one operation.

Another object of the invention is to provide apparatus constructed of soft or friable materials which may be drilled up and washed out of the hole if lost therein.

2

With the foregoing objects as paramount, the invention has further reference to certain features of accomplishment which will become apparent as the description proceeds, taken in connection with the accompanying drawings wherein:

Figure 1 is a view in vertical section taken on line 1—1 of Figure 2 showing one form of the invention, in which the upper section has an annular recess containing heat generating materials.

Figure 2 is a view in transverse section, taken on line 2—2 on Figure 1.

Figure 3 is a slightly modified form of the invention in which a plurality of sections are threaded together, each having Thermit containing recesses therein.

Figure 4 is still another form of the invention, showing a plurality of vertically and circumferentially spaced Thermit recesses in a single, elongated plug.

Figure 5 is a fragmentary view in vertical section of a plug in which the Thermit recesses assume a different form, over which the fusible cover is secured by bolts.

Figure 6 is a fragmentary view in vertical section in which the plug has an elongated Thermit recess, employed in windowing casing.

Figure 7 is a view in transverse section, taken on line 7—7 on Figure 6, and

Figure 8 is a view taken on line 8—8 on Figure 4.

Continuing with a more detailed description of the drawing, reference is primarily made to Figure 1 wherein 10 denotes a section of well casing in which the casing cutting, perforating or windowing apparatus of the invention is suspended.

The device of the invention consists primarily of a sectional plug, the upper section 11 of which is composed preferably of asbestos or plastic, immune or at least partly so to intense heat. The lower end 12 of the section 11 of the plug is reduced slightly in diameter and is externally threaded to be received by the correspondingly threaded lower section 13, formed preferably of refractory or ceramic material. The section 13 is preferably bullet-shaped for ease in lowering the plug into pipe or casing, which is accomplished by means of a wire line or cable attached to a bail 14 affixed to the upper plug section 11. The refractory plug section 13 is made hollow to contain a material of considerable weight, such as lead 15.

Referring again to the upper section 11 of the

plug, it is apparent that the member is provided with an annular recess or groove 16 about its midsection whose concave base is in communication at at least two points with an axial opening 17 in the section 11, by means of lateral openings 18, to which further reference will be made presently.

The annular recess 16 is filled with a quantity of Thermit 19, which is covered by a band or ring 20, of fusible material, suitably held in an annular recess about the plug section 11, which recess is slightly greater in width than the Thermit groove 16.

The plug, composed of the sections 11 and 13 is of a diameter slightly less than the inner diameter of the casing 18 into which it is lowered so that there will be but little clearance between the walls of these elements.

To ignite the Thermit, when the plug is properly positioned in a casing, an electrical current conductor or cable 21 is disposed in the longitudinal opening 17 of the upper plug section, which has separate circuits 22 and 22a, passing through the opening 18 to respective heating elements 23 and 23a, embedded in the Thermit 19 of recesses 16. By completing the circuits through conductors 22 and 22a, heat sufficient to ignite the Thermit 19 is generated in the elements 23 and 23a, respectively, causing the Thermit, in predetermined quantity and location, to react violently, producing sufficient heat to fuse the metal of the casing immediately adjacent to the Thermit.

In the structure shown in Figures 1 and 2, the casing 10 will be entirely severed at the point of operations. In the operation, the band 20 will, of course, be quickly disintegrated.

The other forms and applications of the principle hereinbefore explained, and as shown in the remaining figures of the drawing differ only to the extent that instead of completely cutting the casing, the latter is windowed or perforated. For this reason, the same characters of reference used in preceding views are employed to indicate like parts in these variations.

In Figure 3 is shown a plug composed of internally and externally threaded sections 11 whose recesses 16, containing Thermit 19, may consist of annular cavities or cells and, by virtue of the superimposed relationship of the sections 11, perforations may be made in the pipe in vertically spaced relationship. The size or diameter of the perforations will, of course, be determined by the quantity of Thermit used or, in other words, the size and capacity of the cavities 16 containing the Thermit. In this connection, it is further pointed out that the particular shape of the cavity, i. e., the concaved form of its base is calculated to focus the heat of combustion towards the central point of operations, from which fusion will spread to the maximum range, producing a cut of a width not much greater than that of the Thermit cavity.

In the construction shown in Figure 3, a suitable weighted lower section 13, shown fragmentarily in this figure, is provided.

The construction shown in Figure 4 is not unlike that illustrated in Figure 3 except that instead of a multiplicity of superimposed and interchangeable sections, the plug consists of a single mandrel 11 in which the Thermit recesses or cavities 16 are provided in a similar manner.

In Figure 5, the plug 11 is provided with Thermit recesses or cavities 16 whose bases, instead of being concaved, are substantially flat, as

shown and the Thermit charges 19 are enclosed by bands 20, held in place by bolts or screws 24.

Figures 6 and 7 illustrate a form of plug in which the mandrel 11 is provided with an elongated recess or cavity 16, containing Thermit 19, which latter, upon ignition will produce an elongated window in the casing in which it is suspended. Other features of this form of the invention are identical to others previously shown and described.

Figure 8 shows an alternate cross section of Figures 3, 4 or 6, showing circumferentially divided cavities, either of circular section, as in Figures 3 and 4, or elongated section, as in Figure 6. These would, if ignited simultaneously, provide several circumferentially spaced circular openings or elongated openings in the casing. However, by igniting the charges separately and moving the plug in the hole any predetermined pattern of holes may be obtained.

The operation of the described apparatus would simply be to lower the plug to the desired depth in the casing, ignite the Thermit and withdraw the plug. The molten steel from the melted casing would form in small drops and fall to the bottom of the hole or simply remain mixed with adjacent mud.

Manifestly, the apparatus as shown and described is capable of some modification and such modification as may be construed to fall within the scope and meaning of the appended claims is also considered to be within the spirit and intent of the invention.

What is claimed is:

1. A well pipe cutting apparatus including a solid body of heat resisting material adapted to be lowered into a well pipe and having an outer surface provided with recesses of predetermined depth and size circumferentially spaced about said outer surface, an axial passage extending through said body, a plurality of lateral passages communicating between said axial passage and said recesses, and a mixture of equal molecular parts of iron oxide and aluminum contained in said recesses for presentation to an area of said well pipe to be removed, identical to the area of said recesses, electrical current conducting means in said passages, and means embedded in said mixture energizable by current produced in said latter means for generating heat to effect ignition and consequent fusion of said mixture to melt adjacent areas of said well pipe by physical proximity and contact of said fused mixture.

2. In a well pipe cutting, perforating and windowing apparatus, a plug composed of a solid body of high heat resisting material adapted to be suspended in a well pipe, said plug having an outer surface provided with vertically and circumferentially spaced recesses, a plurality of means extending longitudinally and laterally through said body to said recesses for conveying electrical current thereto from the surface, a mixture of equal molecular parts of iron oxide and aluminum in each of said recesses, a heating element embedded in said mixture and energized by current in said latter means to melt said mixture and cause the same to settle by gravity and expand longitudinally to contact adjacent areas of said pipe.

3. Well pipe cutting apparatus comprising an elongated solid plug of heat resisting composition adapted to be lowered into a well pipe and having circumferentially spaced cells in its longitudinal outer surface, said body being provided with an axial passage extending through said body and a

plurality of lateral passages communicating with said axial passage and said cells, a mixture of nonexplosive heat generating substance in said cells, an electrically energizable means embedded in the mixture in each cell and means in said passages for conveying electrical current to said energizable means to ignite and fuse said mixture and cause the same to flow by gravity against adjacent areas of said pipe to melt the same.

4. In means for cutting out portions of tubular structures by heat; a heat resistant body adapted to be disposed in desired position within a tubular structure, said heat resistant body having an outer surface provided with a plurality of spaced shallow recesses, said recesses being adjacent to the portions of the tubular structure which are to be cut out when said heat resistant body is disposed in desired position within said tubular structure; a body of nonexplosive exothermic mixture in each of said recesses; and means for initiating the chemical reaction of said bodies of exothermic mixture whereby the heat generated by said reaction of said bodies of exothermic mixture will melt out portions of said tubular structure adjacent said recesses.

5. In means for cutting out portions of tubular structures by heat; a body of refractory material adapted to be positioned in desired positions within a tubular structure, said body having an outer surface provided with a plurality of vertically spaced annular grooves; a body of exothermic mixture in each of said grooves; and means for selectively initiating the chemical reaction of said bodies of exothermic mixture whereby the heat generated by the reaction will melt out portions of said tubular structure adjacent said grooves.

6. In means for cutting out portions of tubular structures by heat; a body of refractory material adapted to be positioned in desired positions within a tubular structure, said body having an outer surface provided with a plurality of vertically spaced annular grooves, a body of exothermic mixture in each of said grooves; a means formed of heat destructible material associated with each groove for retaining said body of exothermic mixture within said grooves; and means for selectively initiating the chemical reaction of said bodies of exothermic mixture whereby the heat generated by said reaction will melt said means formed of heat destructible material and will melt out portions of said tubular structure adjacent said grooves.

7. In means for cutting out portions of tubular structures by heat; a body of refractory material adapted to be positioned in desired position within a tubular structure, said body having an outer surface provided with spaced shallow recesses; a

body of nonexplosive exothermic mixture in each of said recesses, said bodies of exothermic mixture being positioned adjacent the portions of the tubular structure which are to be cut out; means formed of heat destructible material associated with each of said recesses for retaining said body of exothermic mixture in said recess; and means for initiating the chemical reaction of said bodies of exothermic material whereby the heat generated by the reaction will destroy said heat destructible means and melt out portions of said tubular structure adjacent said recesses.

8. In means for severing tubular structures by heat; a body of refractory material adapted to be positioned in desired position within a tubular structure, said body having an outer surface provided with an annular groove; a body of exothermic mixture in said groove, said body of exothermic mixture being adapted to be positioned adjacent the tubular structure at the point at which the tubular structure is to be severed; and means for initiating the chemical reaction of said exothermic mixture whereby the heat generated by said reaction will melt said tubular structure adjacent said groove.

9. In means for cutting out portions of tubular structures by heat; a body of refractory material arranged about a longitudinal axis and adapted to be positioned in desired position within a tubular structure, said body having an outer surface provided with an elongated recess extending parallel to said longitudinal axis; a body of nonexplosive exothermic material in said recess, said body of exothermic material being adjacent to the portion of the tubular structure which is to be cut out when said body of refractory material is disposed in desired position within said tubular structure; and means for initiating the chemical reaction of said body of exothermic material whereby the heat generated by said reaction of said bodies of exothermic material will melt out an elongated portion of said structure adjacent said recess.
